UNITED STATES PATENT OFFICE.

DANIEL J. VAN VLACK, OF SILVER CREEK, AND FREDERICK L. MATHER,
OF BROCTON, NEW YORK.

WIRE-STRETCHER.

SPECIFICATION forming part of Letters Patent No. 531,813, dated January 1, 1895.

Application filed July 9, 1894. Serial No. 516,904. (No model.)

To all whom it may concern:

Be it known that we, DANIEL J. VAN VLACK, residing at Silver Creek, and FREDERICK L. MATHER, residing at Brocton, in the county 5 of Chautauqua and State of New York, citizens of the United States, have invented a new and useful Improvement in Wire-Stretchers, of which the following is a specification.

This invention relates to that class of wire 10 stretchers or clamps which consist essentially of a pair of levers provided in rear of their fulcrums with gripping jaws between which the wire is clamped, and which are capable of grasping a wire at any point between its 15 ends as well as at its ends.

Our invention has for its object to produce a stretching device of this character which is readily applied to and removed from the wire and in which the pivots of the clamping 20 levers are relieved from strain.

In the accompanying drawings: Figure 1 is a sectional elevation of our improved wire stretcher showing a wire between its jaws. Fig. 2 is a cross section thereof in line 2—2, 25 Fig. 1.

Like letters of reference refer to like parts in both figures.

A A represent the clamping levers of the stretcher which are pivotally attached at their 30 front portions to a head or casing B by transverse rivets or bolts c, each clamping lever being attached to the casing independently of the other.

d represents the gripping faces or jaws 35 which are formed on the opposing portions of the two levers, a short distance in rear of their pivots and which are preferably corrugated, as shown in Fig. 1, so as to form a bend in the wire, whereby the same is effectually 40 prevented from slipping in the jaws.

The portions of the clamping levers on which the gripping jaws are formed are substantially parallel in their closed position, while the handles or main portions of the 45 levers diverge rearwardly and are connected by links E E or other means with a draft ring F to which any ordinary stretching tackle may be attached.

The casing B is open-ended for the passage 50 of the wire and comprises a bottom plate b,

side walls b', arranged at right angles to the bottom plate, and lips or flanges b² projecting inwardly from the upper portions of the side walls and separated by a space or aperture b³ through which the wire enters between the 55 gripping jaws. The pivots c pass through the bottom plate of the casing, the flanges b² and the openings a in the clamping levers.

The rear faces a' of the clamping levers, located opposite the jaws d are so arranged 60 relatively to the adjacent side walls of the casing that as soon as the gripping jaws close upon the wire, such rear faces bear against the side walls and rock on the same as a fulcrum, thus transferring the fulcrums of the 65 levers from the pivots c to said rear faces and relieving the pivots from strain. To facilitate this action of the levers, their rear faces are made convex, as shown. In order to remove the strain wholly from the lever 70 pivots the pivot-openings of the clamping levers are made sufficiently larger than the pivots to prevent contact of the latter with the walls of the openings when the jaws are closed, as shown in Fig. 1. The pivots thus 75 serve merely to connect the clamping levers to the casing and retain them in their proper relative position, while the strain of the levers is borne solely by the casing.

By this construction the wire stretcher is 80 capable of withstanding considerable strain without liability of breaking. As the wire enters between the gripping jaws from the side of the casing the stretcher can be readily applied to the wire at any desired point and 85 be as readily removed after stretching the same.

We claim as our invention—

1. The combination with a head or casing, of 90 clamping levers arranged to fulcrum against said casing and provided on their opposing faces with gripping jaws, and retaining devices connecting the clamping levers with said head or casing, substantially as set forth.

2. The combination with a head or casing 95 consisting of a bottom plate, side walls, and lips or flanges projecting inwardly from said side walls, of clamping levers provided on their opposing faces with gripping jaws and on their rear sides, opposite said jaws, with 100

fulcrum faces adapted to bear against the side walls of the head or casing, and pivots passing through the bottom plate and flanges of the casing and the clamping levers in front 5 of the gripping jaws of the latter, the pivot openings of the clamping levers having sufficient play on said pivots to relieve the latter from strain, substantially as set forth.

Witness our hands this 27th day of June, 1894.

DANIEL J. VAN VLACK.
FREDERICK L. MATHER.
